US00D699528S

(12) **United States Design Patent**
Randolph et al.

(10) **Patent No.:** **US D699,528 S**
(45) **Date of Patent:** **** Feb. 18, 2014**

(54) **SPADE BLADE**

(71) Applicant: **Ames True Temper, Inc.**, Camp Hill, PA
(US)

(72) Inventors: **David Randolph**, State College, PA
(US); **James M. Wagner**, Lewistown,
PA (US); **Cloyd R. Shawver**,
Lewistown, PA (US); **Jeff Koenig**,
Mechanicsburg, PA (US)

(73) Assignee: **Ames True Temper, Inc.**, Camp Hill, PA
(US)

(**) Term: **14 Years**

(21) Appl. No.: **29/455,135**

(22) Filed: **May 17, 2013**

(51) LOC (10) Cl. **08-01**

(52) U.S. Cl.

USPC **D8/10**

(57) **CLAIM**

The ornamental design for a spade blade, as shown and described.

DESCRIPTION

FIG. 1 is an isometric view of the spade blade;

FIG. 2 is a top view of the spade blade;

FIG. 3 is a bottom view of the spade blade;

FIG. 4 is a right view of the spade blade;

FIG. 5 is a left view of the spade blade;

FIG. 6 is a front view of the spade blade; and,

FIG. 7 is a back view of the spade blade.

The broken lines in the drawings depict environmental subject matter only and form no part of the claimed design.
